TOWEL CABINET

Herbert W. Crowson, New York, N. Y., assignor
to Pullclean Manufacturing Corporation,
Bridgeport, Conn., a corporation of Delaware

Application May 25, 1933, Serial No. 672,759

12 Claims. (Cl. 312—38)

This invention relates to towel cabinets of the type adapted to contain a so-called "continuous" towel, that is, a long length of towel, usually in roll form, which is adapted to be drawn outwardly through an opening in the cabinet in suitable predetermined lengths for drying purposes. This type of cabinet is usually provided with a roller mounted therein in position to be engaged and rotated by the towel as the latter is withdrawn from the cabinet, the said roller being effective by the alternate stopping and releasing of the same, to control the feed of the engaged towel from the cabinet. The soiled end of the towel is drawn back into the cabinet, in position out of contact with the clean towel, by a take-up mechanism which usually comprises a supporting roll and a cooperating winding roll, the latter being operatively connected with the feed roll to be actuated thereby to wind the soiled towel on its supporting roll at substantially the same rate as the clean towel is withdrawn from the cabinet.

In "loading" the cabinet, the roll of clean towelling is placed on a shelf or other support therein, after which the loose end of the towelling is drawn from the cabinet over the feed roll in sufficient length to form a loop at the outside of the cabinet and is then passed back into the cabinet to the take-up mechanism. When the cabinet is loaded, the towel usually passes from the feed roll to the take-up roll over certain intermediate guide and tensioning devices. The threading of the towel about these several elements in the usual way is a somewhat difficult and tedious operation, requiring considerable time. With this in mind, it has been one of the main objects of the present invention to provide an improved cabinet permitting of the quick and easy loading of the cabinet, even by an inexperienced operator.

In the use of cabinets of the present type, there is a tendency on the part of the users to draw off more towelling for each individual use than is actually required and in this way adding unnecessarily to the expense of maintaining the cabinet. With this in mind, it has been a further object of the present invention to provide these cabinets with an improved means for so controlling the delivery of the towelling as to cause the user to draw off only such limited lengths of same as may be required.

The invention consists in the novel constructions and arrangements of parts as hereinafter described and claimed, and as illustrated in the accompanying drawings, in which—

Fig. 1 is a front elevation of a cabinet embodying my invention, with a part of the front section or door broken away on the line 1—1 of Fig. 2 in order to show the parts at the rear thereof within the cabinet.

Fig. 2 is an end elevation of the same with the casing in section on the line 2—2 of Fig. 1.

Fig. 3 is a top plan with the door opened and with the casing and certain parts on the door in section on the line 3—3 of Fig. 2.

Fig. 4 is a sectional detail illustrating the method of loading the cabinet.

Fig. 5 is an enlarged detail, partly in section, showing the stopping and releasing means for the delivery feed roll, the parts being here shown in roll stopping position.

Fig. 6 is a similar view with the parts shown in position for releasing the roll stopping means.

Fig. 7 is another similar view showing the bolt of the stopping means being shifted from inoperative to operative position.

Fig. 8 is a view similar to Fig. 6 but showing a modified form of the stopping and releasing means.

Fig. 9 is a section through line 9—9 of Fig. 8.

Figs. 10 and 11 are plan views, partly in section, of a part of the means for releasing the feed roll stopping means; these views illustrating the parts at different times in their operation.

Fig. 12 is a detail view, partly in section, showing one of the adjustable stops for controlling the vertical position of the pinch roll which cooperates with the towel delivery feed roll.

The cabinet is here shown as comprising an outer casing formed in two sections 2 and 3, the front section 3, constituting a door, being hinged at one of its vertical edges to the rear section 2, as at 4, whereby the casing may be opened to permit of ready access to the interior thereof.

Located within the casing adjacent opposite ends thereof are a pair of frame or bracket plates 5, 5, secured together by suitable tie-rods and being fastened to the casing by bolts, such as 7. These bracket plates provide supports for a plurality of parts to be presently described which function to control the delivery of the clean towelling from the cabinet and the return of the soiled towelling therein.

Supported between the bracket plates is a shelf 8 for the support of the roll of clean towelling, indicated at 1; this shelf, as best shown in Fig. 2, extending in a generally horizontal direction from a supporting cross-rod adjacent the rear of the cabinet, towards the front of the latter where it extends upwardly to a second supporting cross-

rod, the front vertically arranged wall 8' of the shelf serving to retain the roll of towelling on the shelf against the forward pull thereon as produced by the withdrawal of the towelling from the cabinet.

When a roll of towelling has been placed on such shelf, the leading end of the same, as best shown in Fig. 2, is passed upwardly and over the delivery feed roll 10, suitably journalled in the 10 end brackets 5, from thence about a pinch roll 11 engaging the under side of the feed roll, and from thence forwardly through an opening 12 in the front door of the casing to and over a guide roller 13, which latter is journalled in extensions 15 of the brackets 5 projecting through the opening 12 in the door to support the roller at the front side of the latter as shown. From this guide roller 13 the towelling depends in loop form, as at 1, in convenient position for use; the towelling at the 20 rear side of the loop passing backwardly through the opening 12 in the door to a take-up or re-winding mechanism comprising a roller 15 upon which the towelling is wound and a winding roll 16 operative to engage the towelling and wind it 25 upon said roll 15. The winding roll 16 is operated, to function as described, from the feed roll 10 through a suitable drive connection, which, as here shown, comprises a gear train 17, 18 and 19.

The pinch roll 11 is positioned at the under 30 side of the feed roll whereby to cause the towelling to take a substantial wrap about the feed roll in its passage thereover for the purpose of establishing a firm frictional engagement between the same. This is necessary in order to assure rotation of the feed roll by the towelling upon the withdrawal of the latter, whereby to effect simultaneous operation of the operatively connected soiled towelling take-up mechanism. To further assure a close frictional engagement of the towelling 40 with the feed roll, the pinch roll 11 is held with a yielding pressure against the feed roll. This is effected by mounting the pinch roll in journal bearings at the lower ends of a pair of vertically movable slide members 25, 25, which are here 45 shown as passing through guide openings 26, 26 in the upper and lower horizontal flanges 27, 27 of a plate 28 which is attached to the door of the cabinet by suitable fastening means, such as the bolts or screws 29 engaging rearwardly extending 50 end flanges 30 of said plates, as best shown in Figs. 2 and 3. The slide members 25 are held in vertical position for yielding engagement with the under side of the feed roll by spring means to be presently described, and in order to limit their 55 upward movement under the influence of said spring means, whereby the pinch roll will be maintained in its normal vertical position when moved from beneath the feed roll upon the opening of the door, the slide members are each provided with a stop device. This device, as here 60 shown, comprises a bolt 31 connected with the slide member through a vertically elongated slot 32 therein and carrying a block or washer 33 constituting a projection on the slide member for 65 engagement with the under side of the adjacent flange 27 of the plate 28. A vertical adjustment of the washers 33 on the slide members will regulate the position of the pinch roll with respect to the feed roll to give the desired pressure of the 70 pinch roll against the latter and also will permit adjustment of said pinch roll to adapt it for co-operation with feed rolls of varying diameters.

As before stated, it is necessary in cabinets of the present type, in which the feed roll is operated by the withdrawal of the towelling to actuate

the soiled towelling take-up mechanism, and also in which the delivery of the towelling is controlled through the intermittent stopping of the feed roll, that the towelling be maintained in close frictional engagement with the feed roll. For such 5 reason, I provide means to supplement the action of the pinch roll in maintaining such engagement. These means comprise one or more presser plates 35 adapted to act with a yielding pressure against the feed roll to hold the interposed towelling firmly thereagainst in its passage over the same to the pinch roll. Two of these 10 presser plates are here shown, although it will be obvious that only one of sufficient length may be employed if desired. These plates are preferably curved to conform to the surface of the feed roll as shown and are pivotally mounted on a cross-rod 36 extending between and carried by the slide members 25. As a means for holding these presser plates with a yielding pressure 15 against the feed roll, they are formed with arms or extensions 37 above their pivotal connection with the rod 36, with which connect the lower ends of springs 38, which latter at their upper ends connect with the upper stationary flange 25 27 of the plate 28. As said arms extend inwardly 20 at an angle to the presser plates, as best shown in Fig. 2, it will be understood that the upward pull of the springs 38 on said arms act to rock the 25 presser plates on their pivot support inwardly 30 against the feed roll. By employing springs of the proper strength any desired pressure of the presser plates against the feed roll may be obtained.

As before stated, the slide members 25, 25 are 35 adapted to be supported vertically in a manner to hold the pinch roll 11 with a yielding pressure against the under side of the feed roll. Such support may be effected in any suitable way, but in the present instance it is obtained by the springs 40 38 which, acting through their upward pull on the cross-rod 36 on which the presser plates are mounted, thereby exert a like pull on the connected slide members and supported pinch roll. 45

The roller 15 carrying the soiled towelling is provided with end journals which are removably seated in open journal bearings, such as 40, formed in the forward ends of a pair of arms 41, 41 which latter are mounted at their rear ends on suitable pivots 42, 42 adjacent the rear of the 50 cabinet and rigidly connected at a point intermediate of their ends by a cross rod 43 whereby both arms will move as a single unit. Springs 44, 44 connecting at one end with these arms, as at 45, and at their opposite ends with fixed pins 46 on the frame plates, act to hold the supported towelling roller 15 with sufficient pressure against the winding roll 16 as to assure proper winding of the soiled towelling on said roller 15, and at the same time permit of such backward yielding of the arms as may be required to provide for the increasing diameter of the roll of soiled towelling as the latter is wound on the roller. The arms 41, as shown in Fig. 2, are curved downwardly at 55 their forward ends so as to bring the journal bearings therein for the towelling roller in a position at the front side thereof to permit of the convenient placing of the roller therein and its removal therefrom. The connection of these arms 41, 41 by the cross-rod 43 whereby they move as 60 a unitary structure, is of special benefit in that it causes a uniform winding of the soiled towelling on the roller 15. For example, if the towelling has a tendency to wind unevenly on its supporting roll, which would ordinarily result in a greater in- 65 70 75

crease in the diameter of the roll at one end than at the other, the even or uniform pressure of the roll of towelling against the winding roll 16 as produced by the rigidly connected spring-pressed arms 41, 41 quickly acts to restore an even winding of the towelling.

With the construction of cabinet as thus far described, the loading operation is accomplished as follows: The door or front section of the cabinet is first opened as shown in Fig. 3. This front section being divided from the rear section at a point almost midway of the depth of the casing, it will expose, when open, practically all of the interior mechanism for convenient access by the operative, as will be clear by reference to Figs. 2 and 3. When the door is thus opened, the pinch roll, presser plates and their associated supporting and operating means mounted on the door, will of course be moved from their normal positions adjacent the feed roll. Thereafter the roll of clean towelling is placed on the shelf 8 and the leading end thereof drawn outwardly over the feed roll 10 and guide roll 13, as shown in Fig. 4, and then connected to the take-up roller 15 by taking a few turns about the latter, after which said roller will be seated in its bearings in the supporting arms 41. The loading of the cabinet as thus far effected is obviously a quick and simple one. The next step is the closing of the door. This operation moves the pinch roll and presser plates to their normal position for cooperation with the feed roll, the pinch roll when thus moved to operative position engaging with the towel and positioning it for passage thereabout from the feed roll to the guide roll 13 as shown in Fig. 2. During the closing of the door, the loop of towelling is drawn outwardly through the opening in the door whereby it will be positioned for use at the exterior of the cabinet upon the final closing of the door as shown.

The plate 28 and its flanges 27, 27 form, with the front wall of the casing, a housing for the springs 38 and their immediate connections which will prevent tinkering with the same by unauthorized persons when the door is open, and which will also prevent contact with the same of the clean towelling when the door is closed.

The means for intermittently stopping rotation of the feed roll for the purpose of limiting the length of towelling drawn off for each individual use is substantially the same as that disclosed in U. S. Letters Patent No. 1,839,721, granted Jan. 5, 1932, except that in the present case it is applied to the take-up winding roll instead of to the feed roll as in the aforementioned patent. As these two rolls however are operatively connected for movement in unison, the functioning of the stopping means obviously is the same irrespective to which of the two rolls it is applied. This stopping means comprises a bolt 50 slidably mounted in a transverse bore 51 formed in a housing block or disk 52 fixedly mounted on the squared end 53 of one of the end journals of the take-up winding roll 16; this bolt being slidably in the bore 51 for movement transversely of the roll and being limited in its sliding movement by the engagement of the journal 53 with the end walls of an elongated groove 55 in the bolt, as shown in Figs. 5 to 9 inclusive.

When a length of towelling is drawn outwardly from the cabinet, thereby causing rotation of the feed roll and a corresponding rotation of the winding roll 16 through the connecting gearing, the bolt 50 will be moved in its bore, in a manner to be presently described, so as to project one

end thereof, indicated at *a*, beyond the periphery of the disk. During continued rotation of the roll, the said projecting end of the bolt is brought into contact with a stop device 60, as shown in Fig. 5, and so stops rotation of both rolls 16 and 10 and thereby further withdrawal of the towelling engaged by the roll 10. Subsequently, to obtain another length of the towelling, the bolt is released from the stop to permit another rotation of the rolls. For effecting such release of the bolt, the stop device 60, here shown as fixed to the upper end of a bar 61 pivotally mounted at 62 on the end wall of the front section or door, is pushed inwardly against an end face 63 of the bolt to move the projecting end of the latter into the bore of the disk 52, as shown in Fig. 6, after which the stop, upon being released by the user, will be automatically returned to its normal position and out of engagement with the bolt to permit further rotation of the rolls, by means of a pull spring 64 connecting at one end with the lower end of the bar 61 and at its opposite end with a fixed pin 65 on the end wall of the door.

When the bolt 50 has been shifted to releasing position, its rear end is thereby projected beyond the periphery of its housing disk, as shown in Fig. 6. This rear end is provided with an inclined or cam surface 69 which, when brought into wiping engagement with the end of the stop device upon the succeeding rotation of the roll 16, as shown in Fig. 7, serves to positively shift the bolt in an endwise direction in its bore 51 to project its opposite or stopping end beyond the periphery of the disk into position for subsequent engagement with the stop device. When the bolt has been so shifted, it is held in such position during the subsequent one-half turn of the roll by means of a spring 70 which acts on the bolt in a direction transversely thereof to hold it stationary in frictional engagement with the wall of its containing bore.

In mechanisms for causing intermittent rotation of the towel delivery feed roll as heretofore in general use, and as disclosed in the aforesaid Patent No. 1,839,721, the stop bolt is released from the coaxing stop member by a single push-button or like device, requiring the use of only one hand by the user of the cabinet. As hereinbefore stated, however, it has been found in the use of cabinets of this type, that is, those in which the stop may be released by a single push-button or like device, that there is a tendency on the part of the users to draw off in successive lengths more towelling than may be actually required, this being readily accomplished by the user employing one hand to grasp and draw off towelling while employing the other hand to release the stop. To avoid this, the stop releasing mechanism of my present invention is such as to require the employment of both hands to thereby make it necessary that the user release his grasp on the towel at each withdrawal of a measured length in order to more effectually break the continuity of the towel delivery operation and in this way have a tendency to limit the withdrawals to only the amount required. In carrying this part of my invention into effect, I provide a rod 71 which extends transversely of the cabinet in position at the rear side of the face wall, with one end pivotally mounted on one end wall of the door section and the other end pivotally connected with the stop releasing bar 61 at a point above its pivot 62. The pivoted end connections of this bar may be effected in any suitable way. As here shown, its connection with the end wall is made by a re-

duced section 71' of the rod being loosely seated within an open socket 72 in a plate or block 73 fixedly attached to the casing, and its connection with the bar 61 is made by a reduced section 74 of the rod being loosely seated within a socket 75 in said bar, as shown in Figs. 7 and 8. A second rod 76, which I term an "actuating rod", is pivotally connected intermediate of its ends with the first rod 71 at a point intermediate of its ends 10 by a suitable connection, such as the bolt or pin 77. This actuating rod, as here shown, extends substantially the full width of the cabinet and has a pivotal connection at its opposite ends with a pair of push-buttons 80, 80 which are slidably 15 mounted in bearings 81, 81 fixed in the front wall or door of the cabinet, with their outer ends positioned at the exterior of the cabinet for convenient engagement by the user, as shown. With this arrangement of parts, when the user pushes 20 one of the buttons inwardly to its limit, as the right-hand button in Fig. 7, it simply acts to rock the connected actuating rod on its pivot 77 without effecting any corresponding movement to the rod 71 which connects with the stop releasing bar 25 61, thus making it necessary for the user to simultaneously push in both buttons to effect a rearward bodily movement of the actuating rod 76 at its point of connection with the rod 71 in order to operate the latter and cause a stop releasing 30 movement to the bar 61 as shown in Fig. 8. In other words, a movement of the actuating bar produced by the operation of only one push-button, as in Fig. 7, leaves the releasing bar 61 in the position shown in Fig. 5, while a movement 35 of the actuating bar produced by the simultaneous inward movement of both buttons, as in Fig. 8, effects the releasing movement of the bar 61 shown in Fig. 6. It will of course be understood that the spacing of the push-buttons may be varied as desired, provided that they are spaced 40 sufficiently far apart as to necessitate the use of both hands in operating the same.

As here shown, the stop device 60 constitutes both a stop device and a stop releasing device. If desired however, separate devices may be employed for the performance of these two functions. For example, a stop member, such as shown at 85 in Figs. 8 and 9, may be fixed to the inner wall of the front casing for stopping engagement with the projecting end of the bolt 50 in the same way as done by the device 60, and the member 86 shown in these Figs. 8 and 9, as carried by the bar 61 in position at one side of the stop 55 80, may be operated by said bar to function as a stop releasing device in the same manner as done by the combination stop and releasing device 60. Thus it will be understood that the double push-button feature of the present stop releasing means is not dependent for its releasing operation upon any particular form of feed roll stop mechanism.

What I claim is:

1. A towel cabinet having a door normally closing the same, a feed roll mounted on the cabinet over which the clean towel passes for delivery to the user, a pinch roll cooperative with said feed roll for maintaining the towel in frictional engagement therewith, a presser member also cooperative with the feed roll for holding the towel in frictional engagement therewith, supporting means on the door carrying both the said pinch roll and presser member, and means normally holding said supporting means in position with the pinch roll and presser member in yielding engagement with the feed roll.
2. A towel cabinet having a door normally clos-

ing the same, a feed roll mounted on the cabinet over which the clean towel passes for delivery to the user, a pinch roll cooperative with said feed roll for maintaining the towel in frictional engagement therewith, supporting means for the 5 pinch roll comprising a pair of bars slidably mounted on the door for vertical movement, stop means for limiting the vertical movement of said bars with the supported pinch roll in position for cooperation with the feed roll, and spring means 10 yieldingly holding the bars in engagement with said stop means.

3. A towel cabinet having a door normally closing the same, a feed roll mounted on the cabinet over which the clean towel passes for delivery to the user, a pinch roll cooperative with said feed roll for maintaining the towel in frictional engagement 15 therewith, supporting means for the pinch roll comprising a pair of bars slidably mounted on the door for vertical movement, stop means for limiting the vertical movement of said bars with the supported pinch roll in position for cooperation with the feed roll, spring means 20 yieldingly holding the bar in engagement with said stop means, and a housing on the door enclosing 25 said spring means.

4. A towel cabinet having a feed roll over which the clean towel passes for delivery to the user, a pinch roll cooperative with said feed roll for maintaining the towel in frictional engagement 30 therewith, supporting means for the pinch roll comprising a pair of vertically arranged bars carrying the pinch roll at their lower end, means supporting said bars for sliding movement, a cross rod connecting said bars and movable therewith, 35 a presser plate mounted on said cross rod, and means yieldingly holding said bars with the supported pinch roll and presser plate in cooperative relation to the feed roll.

5. A towel cabinet having a door normally closing the same, a feed roll mounted on the cabinet over which the clean towel passes for delivery to the user, a pinch roll cooperative with said feed roll for maintaining the towel in frictional engagement 40 therewith, supporting means for the pinch roll mounted on the door and comprising a pair of vertically arranged bars having lower inwardly turned ends supporting the pinch roll in position for engagement with the under side of the feed roll when the door is closed, means 45 supporting said bars for sliding movement, and means normally holding said bars with the supported pinch roll in yielding engagement with the feed roll.

6. A towel cabinet having a feed roll over which the clean towel passes for delivery to the user, a take-up feed roll having a driving connection with said delivery feed roll, a pivoted frame having a part thereof positioned adjacent the take-up feed roll and provided with open journal bearings, a take-up roller for the soiled towel removably journaled in said bearings, and means yieldingly holding the pivoted frame in normal position with the supported take-up roller bearing against the adjacent feed roll.

7. A towel cabinet having a door normally closing the front side thereof, a feed roll over which the clean towel passes for delivery to the user, a take-up feed roll having a driving connection with said delivery feed roll, means supporting said take-up feed roll in a position forward of the side walls of the cabinet when the door is open, a frame pivotally mounted within the cabinet and having a part thereof projecting forwardly of the cabinet when the door is open to a

position adjacent the take-up feed roll, said projecting part being provided with open journal bearings for the removable support of a take-up roller, and means yieldingly holding the pivoted frame in normal position with the supported take-up roller bearing against the adjacent feed roll.

8. In a towel cabinet, the combination with a feed roll over which the clean towel passes for delivery to the user, and means for intermittently stopping rotation of said roll, of means for releasing said stopping means comprising two spaced manually operable actuating devices, and means operable only by an actuation of both said devices to release the stopping means.

9. In a towel cabinet, the combination with a feed roll over which the clean towel passes for delivery to the user, and means for intermittently stopping rotation of said roll, of means for releasing said stopping means comprising two spaced manually operable actuating devices mounted on the cabinet with their operating ends in position for engagement at the exterior side of the cabinet, and means operable only by an actuation of both said devices to release the stopping means.

10. In a towel cabinet, the combination with a feed roll over which the clean towel passes for delivery to the user, and means for intermittently stopping rotation of said roll comprising a stop member and a slidably mounted bolt carried by the roll for engagement with said stop member,

of means for releasing said stopping means comprising two spaced manually operable actuating devices, and means operable only by an actuation of both said devices to release the stopping means.

11. In a towel cabinet, the combination with a feed roll over which the clean towel passes for delivery to the user, and means for intermittently stopping rotation of said roll, of means for releasing said stopping means including a shiftable member, a second member pivotally connected at a point between its ends with said shiftable member, and actuating means associated with said second member adjacent its opposite ends.

12. In a towel cabinet, the combination with a feed roll over which the clean towel passes for delivery to the user, and means for intermittently stopping rotation of said roll, of means for releasing said stopping means including a shiftable member, a second member pivotally connected at a point between its ends with said shiftable member, actuating means associated with said second member adjacent its opposite ends, and means limiting the swinging movement of said second member about its pivot on the shiftable member whereby a bodily movement of the same in one direction, as effected by pressure against both actuating devices is necessary to effect operative movement of the connected shiftable member.

HERBERT W. CROWSON.
